(57) **CLAIM**

What is claimed is the ornamental design for a putter head, as shown and described.

DESCRIPTION

FIG. 1 is a front left top perspective view showing the putter head of Applicant's new design.

FIG. 2 is a bottom rear right perspective view of putter head of FIG. 1.

FIG. 3 is a front elevation view of the putter head of FIG. 1.

FIG. 4 is a rear elevation view of the putter head of FIG. 1.

FIG. 5 is a left side elevation view of the putter head of FIG. 1, the right side elevation view being an identical mirror image thereto

FIG. 6 is a top plan view of the putter head of FIG. 1.

FIG. 7 is a bottom plan view of the putter head of FIG. 1; and,

FIG. 8 is a left side elevational view of the putter head of FIG. 1. The broken line showing of the golf ball is environment.

The broken lines in the drawings illustrate portions of the putter head and/or environment which form no part of the claimed design.

1 Claim, 5 Drawing Sheets
